CLAIM

The ornamental design for a jack foot pad as shown and described.

DESCRIPTION

FIG. 1 is a perspective view of a first embodiment of a jack foot pad showing my new design;

FIG. 2 is a top view thereof;

FIG. 3 is a bottom view thereof;

FIG. 4 is a front view thereof;

FIG. 5 is a back view thereof;

FIG. 6 is a left side view thereof;

FIG. 7 is a right side view thereof;

FIG. 8 is a perspective view of a second embodiment of a jack foot pad showing my new design;

FIG. 9 is a top view thereof;

FIG. 10 is a bottom view thereof;

FIG. 11 is a front view thereof;

FIG. 12 is a back view thereof;

FIG. 13 is a left side view thereof;

FIG. 14 is a right side view thereof;

FIG. 15 is a cross-sectional view thereof taken along line 15-15 of FIG. 9; and,

FIG. 16 is a cross-sectional view thereof taken along line 16-16 of FIG. 9.

The broken lines in the drawings depict portions of the jack foot pad that form no part of the claimed design.
